UNITED STATES PATENT OFFICE.

FRANK A. LUNDQUIST, OF NEW YORK, N. Y., ASSIGNOR TO WESTERN ELECTRIC COMPANY, INCORPORATED, OF NEW YORK, N. Y., A CORPORATION OF NEW YORK.

SELECTING-SWITCH.

1,283,831.

Specification of Letters Patent.

Patented Nov. 5, 1918.

Application filed August 2, 1916. Serial No. 112,757.

To all whom it may concern:

Be it known that I, FRANK A. LUNDQUIST, a citizen of the United States, residing at New York, in the county of New York and 5 State of New York, have invented certain new and useful Improvements in Selecting-Switches, of which the following is a full, clear, concise, and exact description.

The present invention relates to improvements in selecting switches of that type in 10 which the active contacts or brushes are placed in engagement with the desired passive contact of the switch by a longitudinal and rotary movement of the brush carrying 15 element.

The main feature of the present invention is the provision of a single operating magnet to control both the rotary and longitudinal movements of the brush carrying element, 20 and a slow-releasing magnet to control the sequence of these movements.

Referring to the drawings, Figure 1 shows a side elevation of the skeleton structure of the improved switch, the frame structure and 25 unnecessary parts having been omitted for clearness in illustration; Fig. 2 represents a similar view of a modified form of the invention; and Fig. 3 illustrates a sectional view taken on the line 2—2 of the structure 30 shown in Fig. 2.

Referring to Fig. 1, 5 represents a brush carrying shaft mounted for rotary and longitudinal movement. This shaft carries brushes 6, which engage the contacts 7 35 of a switch bank shown in section at 8. The shaft also carries a rotary ratchet 9 which is driven by a pawl 15 on L-shaped lever 10, which carries armature 10' of the motor magnet 11. This L-shaped lever is pivoted 40 at 12 and is held in retracted position by a spring 13. The vertical arm of the lever is provided with a right angular extension 14, which carries the rotary pawl 15. This vertical arm has its free end bifurcated for a 45 purpose which will be herein later described. The rotary pawl 15 rides on a bearing member 16, so that this pawl in its normal position is out of engagement with the teeth of the rotary ratchet. A holding dog 17 is pivoted 50 at 18 and actuated by a spring 19, so that when the holding dog is free to operate it engages the rotary ratchet teeth. 20 designates an elongated holding member which engages the teeth of the rotary ratchet as 55 soon as the shaft has taken a vertical step.

This member, in the elevated position of the shaft, prevents the rotation of the shaft back to its normal position. 21 indicates a slow-releasing magnet whose armature 22 is pivoted at 23 and held retracted by spring 24. 60 To the free end of this arm there is pivoted a holding pawl 25, which is held out of engagement with vertical ratchet teeth 26 of the shaft by spring 27. This pawl is provided with a resilient arm 57, the purpose of 65 which will be herein later described. A link 28 is attached to the armature 22 and passes through an aperture in the holding dog 17. This link, in the retracted position of armature 22, prevents the holding dog 17 from 70 engaging the rotary ratchet. A spring 29, which has one of its ends attached to a casting 30, carried by the frame, and its other end attached to a collar having a projection which rides in a longitudinal slot 31 in the 75 brush shaft 5, provides for the return of the shaft to its normal rotary position. This spring is wound up when the brush shaft is rotated to an off-normal position. The collar is slidably mounted to permit vertical 80 movement of the shaft at the same time that the shaft is placed under rotary tension. An arm 32 pivoted at 33 and placed under tension by a spring 34 has its arc of rotation limited by the stops 35 and 36. This arm 85 terminates in a hook 37 which engages a collar 38 mounted on the brush shaft. A bell crank lever 39, pivoted at 40, and having one of its ends engaging the collar 38, serves as a 90 latch member to hold the arm 32 in its elevated position. This latch member engages a projection 41 on the arm 32. Another bell crank lever 42 is pivotally carried by the arm 32. This lever carries at one of its ends the tensioned elevating pawl 43, which is 95 normally out of engagement with the vertical ratchet teeth 26 of the shaft. The vertical arm of lever 42 terminates in an angular member 44, which engages with the hook-like structure formed by the projections 45 of the bifurcated end of arm 12 when the shaft has been elevated one step. 100

Having described the structure of the switch, its operation will be briefly given as follows:

When the calling party removes his receiver from the switch hook, line relay 46 will be energized, which causes it to attract its armature. Slow relay 47 is thereupon actuated through a circuit which extends from 110

2

grounded battery, front contact and armature of relay 46, relay 47 to ground. Relay 47 thereupon closes a break point in the operating circuit of magnet 11. At each impulse from the calling dial, line relay 46 retracts its armature and normally closes the operating circuit of motor-magnet 11. This circuit extends from grounded battery, back contact and armature of relay 46, motor-magnet 11, front contact and armature of slow-releasing relay 47 to ground. Armature 10' is actuated in response to each of these impulses and, through the agency of its rotary pawl 15, causes the shaft to take the prescribed number of rotary steps. The first time that the armature 10' was attracted, insulated knob 49 allowed contact springs 50 to come into engagement. This completed an energizing circuit for slow-releasing magnet 21. This circuit extends from grounded battery, magnet 21, conductor 51, vertical normal springs 52, conductor 53, circuit closing springs 50 to ground. Magnet 21 is energized and attracts its armature 22 and since it is slow to release, maintains its armature 22 attracted during the first series of impulses transmitted to the switch, which in this case are the rotary impulses. The armature 22, in being attracted, draws its pawl 25 downward until the pawl engages the first of the vertical ratchet teeth 26. Also, as soon as magnet 22 is attracted, its link 28 releases the holding dog 17, so that this holding member holds the rotary ratchet in the position to which it has been advanced. After the termination of the first series of impulses, the energizing circuit of relay 46 remains uninterrupted for a short interval of time. Relay 46 thereupon attracts its armature and maintains the slow-releasing magnet 47 energized. The operating circuit of magnet 11 is interrupted for a relatively long period, during which time the contact springs 50 of the energizing circuit of magnet 21 are held separated. This magnet is thereupon de-energized and retracts its armature. This movement causes the pawl 25 to elevate the brush shaft one vertical step. The weight of the shaft is removed from the hook 37 of arm 32 and this permits the retractile spring 34 to elevate the arm 32 until it engages the stop 35. The latch member 39 is also released by this movement of the shaft and its spring causes its vertical arm to pass under the member 41 of the arm 32 to hold this arm in a fixed horizontal position. The elevation of arm 32 carries the bell crank lever 42 with its pawl 43 in a vertical direction and causes the angular member 44 to engage the projection 45 of the bifurcated end of arm 10. In response to the next series of directive impulses, the arm 10 which is controlled by the armature 10' of motor-magnet 11, operates the vertical elevating pawl 43 through the agency of bell crank arm 42. During these impulses, the armature 22 of magnet 21 is held in retracted position since its energizing circuit is interrupted at the vertical normal springs 52. When the armature 22 is retracted, the arm 57 engages a projection 61 on arm 32. This causes pawl 25 to engage the vertical ratchet teeth 26. In this position pawl 25 holds the shaft in any position to which it is elevated. When the calling party replaces his receiver the relay 46 is de-energized. This interrupts the circuit of relay 47 at the front contact and armature of relay 46. Relay 47 retracts its armature and completes the energizing circuit of magnet 21. This circuit extends from grounded battery, magnet 21, conductors 51 and 54, vertical off-normal springs 55, conductor 56, armature and back contact 47 to ground. Magnet 21 attracts its armature and draws down the holding pawl 25. In this movement the arm 57, which is attached to pawl 25, is freed from projection 61 which allows spring 27 to draw the holding pawl 25 out of engagement with the vertical ratchet teeth on shaft 5. The shaft 5 under the influence of gravity drops to its normal vertical position. In so doing the rotary ratchet 9 becomes free from the elongated holding member 20 but is immediately engaged by holding dog 17. When the shaft has returned to its vertical normal position, the energizing circuit of magnet 21 is broken at contact springs 55. Magnet 21 retracts its armature and thereby withdraws holding dog 17, so that the shaft is permitted to rotate, under the action of spiral spring 29, to its normal rotary position determined by stop pins 59 and 60. It will be understood that the tooth 26 is provided with a notch which will be in alignment with the pawl 25 when the shaft 5 is in its normal rotary position. This insures that the pawl 25 will be free from the tooth 26, if it has engaged this tooth during the release of the brush shaft.

Referring to Figs. 2 and 3 of the drawings, there is shown a modification of the improved switch structure of the present invention. In this modification after the brush shaft is rotated, instead of being elevated to engage the desired contacts, it is lowered under the control of suitable escapement means until the desired group of contacts is engaged.

Referring to Fig. 2, 101 designates a brush shaft mounted for rotary and longitudinal movement. This shaft carries a brush 102 which engages the contacts 103 of switch bank 104. The upper end of the shaft is provided with a holding tooth 105, which is engaged by a suitable escapement means 106 carried by the armature of slow-releasing magnet 107. A rotary ratchet 108 is carried by the brush shaft, and it is engaged by a tensioned rotary pawl 109, carried by

an extension of an L-shaped arm 110 of motor magnet 111. This arm, which carries armature 110' is pivoted at 112 and its movement is limited in one direction by a 5 stop member 113. The armature 110' carries an insulated knob 138 which controls the circuit closing springs 126. An elongated rotary holding member 114 is pivotally mounted on rod 115 and is actuated by 10 a spring to normally engage the rotary ratchet. This holding pawl is held out of engagement with the rotary ratchet by a latch member in the form of a bell-crank lever 116, pivoted at 117. One of the ends 15 of this latch member engages a projection on the holding pawl, and its other end bears on a collar 118, rigidly mounted on the brush shaft 101. A rotary spring 125 has one end secured to a casing 139, and its 20 other end is attached to a collar provided with a projection which moves in a longitudinal slot 140 in shaft 101. This rotary spring provides for the return of the shaft to its normal rotary position, determined 25 by stops 136 and 137. Vertical movement of the shaft is brought about by means of an escapement member 119 which engages vertical ratchet teeth 120 of the shaft. This escapement member is carried at one end of 30 an arm 121, and is provided with a hook 130 for engagement with hook 131 of L-shaped arm 110. The arm 121 is pivoted at 122, and is provided near one of its ends with a hook 123 which engages collar 124. An insulated knob 141, carried by arm 121, controls circuit-closing springs 142 which are included in the operating circuit of slow-releasing magnet 107. The lower end of 35 the brush shaft is provided with a flat elongated bar 132 which is adapted to be engaged by the constantly revolving roller 133. This engagement takes place when the roller 134, carried by the armature of restoring magnet 135, forces the bar 132 40 against the revolving roller 133.

The operation of the switch is briefly as follows: The motor-magnet 111 is intermittently energized and deenergized in response to impulses from the calling dial. This 50 causes the armature of magnet 111 to drive the rotary ratchet through the prescribed number of steps and winds up the rotary spring 125. At the first attraction of armature 110, circuit-closing springs 126 are momentarily closed and the slow-releasing magnet 107 is energized over a circuit from grounded battery, circuit-closing springs 126, circuit contacts 142, slow-releasing magnet 107 to ground. Magnet 107 is energized 55 and attracts its armature. This causes the tooth 105 on the brush shaft to escape from pallet 127 and to be supported by pallet 128. In this and the normal position of the shaft, arm 121 is supported by hook 123 from collar 124. At the termination of the first se-

ries of impulses, however, the armature of relay 107 is retracted and the brush shaft is no longer supported by the escapement means 106. The shaft descends until arm 21 engages the stop 129, in which position the 70 energizing circuit of slow-releasing magnet 107 is broken at springs 142 and the shaft is suspended by the escapement means 119. This escapement means is provided with a hook 130 which now engages a hook 131 on 75 the armature 110 of the motor-magnet 111. In response to the next series of directive impulses, the arm 110 actuates the escapement 119 and causes the shaft to be lowered step by step. 80

It should be noted that the restoring magnet 135 is deenergized during the period intervening between the initiation of the call and its termination. When restoring magnet 135 is energized at the close of conversation, roller 134 carried by the armature of this magnet, forces the bar 132 into engagement with the constantly rotating roller 133 and elevates the shaft until the pallet 127 of escapement means 106 engages and supports the brush shaft by tooth 105. When the brush shaft is restored to its normal vertical position, latch member 116 is actuated by collar 118 to throw the rotary pawl out of engagement with the rotary ratchet. The 90 rotary spring 125 then restores the shaft to its normal rotary position, determined by stops 136 and 137. 95

It will be understood that the present invention is capable of many variations and that it may be used in any field where selecting switches may be employed. The present disclosure is merely illustrative of the device and the scope of this invention will be limited only by the appended claims. 100

What is claimed is:

1. In a selecting switch, passive contacts, active contacts mounted for engagement with said passive contacts through two series of movements, a single actuating means 110 for operating said active contacts, and means including electromagnetic means responsive to the first impulse of a series of impulses and remaining actuated throughout the series for controlling these movements. 115

2. In a selecting switch, passive contacts, active contacts mounted for engagement with said passive contacts through two series of movements, a single electromagnetic means responsive to each impulse of a series 120 for operating said active contacts, and means including electromagnetic means responsive to the first impulse of a series of impulses and remaining energized throughout the series for controlling these movements. 125

3. In a selecting switch, passive contacts, active contacts mounted for movement in two directions, a single actuating means for operating said active contacts, and means including electromagnetic means responsive to 130

the first impulse of a series of impulses and remaining actuated throughout the series for controlling the direction of the movement of said last mentioned contacts.

5. In a selecting switch, passive contacts, active contacts mounted to move into engagement with the desired passive contacts, a brush-carrying element mounted for rotary and vertical movement to which said active contacts are secured, a single actuating means for operating the brush-carrying element, and means including a magnet responsive to the first impulse of a series of impulses and remaining actuated throughout the series for controlling the proper sequence of the rotary and vertical movements.

5. In a selecting switch, fixed contacts, a vertical shaft provided with vertical ratchet teeth and rotary ratchet teeth mounted for vertical and rotary movement, movable contacts secured to said shaft, a rotary pawl and a vertical pawl for operating said shaft,

an electromagnet, an angular arm actuated by said electromagnet to successively operate said pawls, and a slow-releasing magnet 25 which moves the shaft in a vertical direction to control the sequence of operation.

6. In a selecting switch, fixed contacts, a vertical shaft mounted for vertical and rotary movement and provided with vertical 30 and rotary ratchet teeth, movable contacts carried by said shaft, an arm carrying means to move the shaft in a vertical direction, an electromagnet, an angular arm provided with a rotary pawl, said angular arm being 35 actuated by said electromagnet, and a slow-releasing magnet whose armature operates at the close of the rotary steps to bring the vertical moving means into engagement with said angular arm.

In witness whereof, I hereunto subscribe my name this 31st day of July A. D., 1916.

FRANK A. LUNDQUIST.
